Primary Examiner—Gary D. Watson*Attorney, Agent, or Firm*—Brown, Martin, Haller & McClain[57] **CLAIM**

The ornamental design for a seat, as shown and described.

DESCRIPTION

FIG. 1 is a front perspective view of a seat in a sofa configuration, showing my new design;

FIG. 2 is a side elevational view, the opposite side being a mirror image thereof;

FIG. 3 is a rear view thereof;

FIG. 4 is a front perspective view of a loveseat configuration of the seat;

FIG. 5 is a side elevational view, the opposite side being a mirror image thereof;

FIG. 6 is a rear view of the loveseat configuration;

FIG. 7 is a front perspective view of an armchair configuration of the seat;

FIG. 8 is a side elevational view, the opposite side being a mirror image thereof; and,

FIG. 9 is a rear view of the armchair configuration.
